FEED TABLE

Charles F. Bamford, Portland, Oreg.

Application March 25, 1947, Serial No. 737,043

4 Claims. (Cl. 198—110)

1

My invention relates to a feed table for any type of production machine in which it is necessary to separate the feed table from the production machine at frequent intervals. It has been considered necessary under such circumstances, heretofore, either to make the feed table portable, that is, of such light construction that it may be manually moved out of juxtaposition with the producing machine, or to provide some type of mechanism by which power may be utilized for spacing said machines apart.

I have discovered that if a feed table is formed upon a stationary frame having a top reciprocably mounted thereon and having feeding belts rotatable about said top, said top may be shifted and the belts may be driven by a single endless belt or chain. This may be done only if the operating drag of the belt elements is substantially greater than the frictional drag of the top upon said frame. That is to say, the table operates between two limits and it is desirable that it move with little friction. If the feeding belts drag upon the top of the feed table, they interpose an operating drag or friction which is substantially greater than the frictional drag of the top over the fixed portion of the frame. This is particularly true if rollers or anti-friction bearings are provided between the frame and its top. Then, if the driving motor is reversed after it has been off bearing, for example, the first movement would be that the table top is moved away from the discharge side of the machine until it reaches the other limit of its travel. The belts then would tend to feed towards the machine, which is not necessary in the usual case. The top is spaced from the machine and access can be had between the feed table and the production machine.

All that is necessary to do to cause the table top to move back into its original position is to energize the motor in the direction it first turned to discharge material away from the machine. The rotation of the motor and its operating gear will first cause the table top to move back into its original position against the stop, and will then then cause the belt to rotate. All of these things may be done without any loss of power, any complicated structures, and very speedily.

The details of my invention and the mode of operation thereof are further described with reference to the accompanying drawings, in which:

Fig. 1 is a longitudinal section taken through an outfeed table embodying my invention, said

2

figure being taken on the line 1—1 in Fig. 4; it shows the table top moved towards the left, which is the position it would occupy if it were moving boards or similar articles from left to right as shown diagrammatically by arrows;

Fig. 2 is a similar section, except that it shows the position of the top as it would be arranged when the direction of the belt is reversed; at the right between Figs. 1 and 2 is shown two lines to indicate the degree of movement of the top caused by the reversal of the motor;

Fig. 3 is an enlarged fragmentary section taken on the line 3—3 in Fig. 2, showing the manner in which rollers are provided in guides to cause the table to move along a true path and with the least frictional drag;

Fig. 4 is an end elevation taken substantially on the line 4—4 in Fig. 1, portions, however, being shown broken away to disclose operating details; and

Fig. 5 is a cross-sectional view taken on the line 5—5 in Fig. 1, showing the arrangement of the operating parts of said feed table.

A feed table embodying my invention comprises a fixed frame 1, preferably made of a number of joined structural members. It is equally feasible, however, to cast it of iron, or to provide any suitable frame which has the required strength and rigidity. When made of structural frame members, said frame preferably comprises four corner members 2, 2a, 2b and 2c, which are tied together at the side of the frame by a pair of longitudinal members 3 and 3a. The ends are tied together by two transverse members 4 and 4a.

A motor, such as an electric motor 5, is carried by said frame, and some type of speed reducer 6 is operatively joined thereto by a belt 7. This cuts the motor speed to a speed usable in connection with the feeding and manipulation of said feed table. Extending from the speed reducer on a shaft 6a thereof is a sprocket or pulley 8. The drawings show this and its associated flexible transmission element in more or less diagrammatic form. It is to be understood that this connection might be a pulley and belt, a sprocket and chain, a link belt and drive, or any other type of power transmission which is deemed efficient and appropriate. Adjacent said mechanism is a vertical structural member 9, a short angular support 10, and a transverse angular support 11, said parts being joined together. As is shown in Figs. 1 and 2, pulleys or sprockets 12 and 12a are rotatably supported on the angular support 10. They are spaced above and straddle

the pulley or sprocket 8 which is directly joined to the speed reducer 6 and which serves as the main power take-off.

Longitudinally slideable on said fixed frame 1 and supported by a plurality of rollers 26 is a top structure 13. This comprises a roof plate 14 extending completely across the top and having pendent side edges 14a. Said roof structure is strengthened at spaced intervals by transverse stiffening angles 15. A channel element 16 at each side is welded to the pendent side edges 14a and it is joined to the transverse strengthening angles 15, so as to provide a strong and rigid structure. Said channel elements serve as guide ways for supporting rollers 26 which they engage. End caps 17, in pairs at each end, provide journals for shafts 18-18a, which carry a series of crown faced pulleys 19, 19a and 19b. Said crown faced pulleys are spaced apart on the shaft as indicated in Fig. 4, and each carries an endless belt 20, 20a or 20b. Said belts are quite wide relatively to the width of the table top; that is, they occupy a substantial portion of the overall width thereof, as is shown most clearly in Figs. 4 and 5.

On the shaft 18, also, is a pulley or sprocket 21, and spaced therefrom on the channel 16, about two-thirds of the way to the other end of the top structure 13, is a bracket 22 carrying a pulley or sprocket 23. Located adjacent the pulley or sprocket 21 is a hold-down pulley or sprocket 24. An endless operating chain or belt 25 passes in succession about the driving sprocket or pulley 8 (on the speed reducer), the pulley 12, pulley or sprocket 21, under the hold-down pulley or sprocket 24, about the pulley or sprocket 23, and then about the pulley or sprocket 12a. Power thus is transmitted from the motor, through the speed reducer, to the main drive sprocket or pulley 8, thence through said endless operating chain or belt to the sprocket or pulley 21, which is keyed to shaft 18. This provides a drive for the belts 20, 20a and 20b, and also provides means by which the top structure 13 may be moved upon the frame 1. As has been stated, the top structure is supported on said frame 1 by rollers 26. These are carried by shafts 27, supported by the upper transverse members 4a, in the manner shown in Fig. 4. That is to say, each shaft 27 is welded or otherwise secured to one of the transverse members 4a, and a roller 26 is freely mounted on each of the ends thereof, being held in proper running relation, within the outstanding flanges 16a of channel 16, upon the reduced portion 27a of the shaft, by a nut and washer 27b. The channel element 16 is welded to the pendent side edge 14a of the roof plate 14, and provides a smooth, straight track which the rollers 26 engage. There is sufficient working clearance between the rollers and the internal faces of the lateral flanges 16a of the channel so that proper operation may result. That is to say, there is sufficient clearance to provide for operation, but not too much clearance to produce loose or sloppy action.

Extending through the lateral flanges 16a of the channel element 16 are bolts or other types of stops 28, which engage the rollers 26. That is to say, said bolts or other stops prevent the rollers from moving past the point where they intersect the channel iron. In Figs. 1 and 2, the rollers are shown in abutment with said stops, left and right, respectively. In Fig. 1, a left-hand roller is shown in abutment with the stop which defines the ultimate movement of the top

structure towards the left, as viewed in that figure. In Fig. 2, another roller is shown in abutment with a stop, and this represents the maximum movement of the top structure towards the right. This degree of shift is shown diagrammatically by the value x shown between two arrows leading to two extension lines. The limits, of course, may be arbitrarily set, and this determines the travel of the table top. These limits may be varied somewhat widely. A movement of thirty-six to forty-eight inches is usually sufficient, because the principal purpose for shifting said table top is merely to provide access, and this much space normally is sufficient.

The shift in direction of the top, and the general manner in which said feed table operates, are as follows:

The motor 5 is reversible, and to this end, I show a reversing switch 5a diagrammatically extending from the side of the table, having a switch finger 5b thereon. This may be such as a drum-type reversing switch, and the operation thereof is well known in the art. I have not attempted to disclose the electric circuits for the drive, because they, also, are well known and play no specific part in my present invention. Suffice it to say that the switch is capable of stopping the motor or supplying power to the motor to cause it to rotate in either direction. In Fig. 1, power has been applied to the motor, causing the endless operating chain or belt to move clockwise about its course over the several sprockets or pulleys. It will also cause the belts 20, 20a and 20b to move similarly, these movements being indicated by arrows in said figure. In Fig. 2, the operation has been reversed, as is indicated in arrows, to cause said parts to be rotated counter-clockwise.

Let us assume that in Fig. 1 the feed table is off bearing from a production machine discharging from a point close to the section line 4-4. If it is a slicer, the slides are discharged onto the top and the belts discharge them towards the right and over the end at the right of the top structure 13. It is now desired to move said table top away from said machine. This is accomplished merely by reversing the motor switch. This will cause the table top to move to the position shown in Fig. 2. It, of course, will cause the belts to rotate in the opposite direction after the table is arranged at Fig. 2, but this is of no consequence because it is out of position. When the motor is again reversed, the table is moved back to its original position, namely, the one shown in Fig. 1. This is brought about by reason of the fact that the belts 20, 20a and 20b exercise a substantial operating drag as they move across the table top 13. The movement of the top structure upon its frame offers less operating drag, because said rollers are of substantial diameter and they rotate quite freely. Also, the various pulleys and sprockets which the endless operating chain or belt 25 engage are quite small and are preferably provided with anti-friction bearings. Thus, when power is applied at the shaft 18, both to drive the belts 20, 20a and 20b and the remainder of the endless operating chain or belt 25, the great resistance to movement of said belts causes the power applied through said endless operating chain or belt first to pull the table in the direction opposite to which the belts tend to move. When the table top has moved to its limits, however, then the power of the motor is free wholly to move the belts and does so. This operating drag, although being initially

substantial, does not absorb any substantial portion of the power which should be applied to the belts for moving products thereover. That is to say, the belts exercise substantial static friction but little moving friction, as the table top is smooth and the belts move quite readily thereover. Said static friction, however, is sufficient to permit the tensioning of the endless operating chain or belt 25 to shift the table top initially before power is applied to the belts 20, 20a and 20b.

I claim:

1. A manipulable feed table comprising a frame, a structural top slidably mounted thereon, said top being supported to reciprocate easily along a fixed path between two termini, journaled rollers at the ends of said structural top, an endless belt element encircling said rollers and frictionally engaging the latter, said belt element overlying and bearing upon said top intermediate said rollers and defining, with said top, a work supporting surface, a rotary operating element secured to one of said journaled rollers, a motor-driven operating element secured to said frame, and an endless flexible transmission member engaging said operating elements, the operating drag of said belt element being substantially greater than the frictional drag of said top upon said frame, said transmission element being operatively arranged to shift the top in one direction and to drive the belt in the opposite direction, whereby when power is applied, said rotary operating element tends to travel along the endless flexible transmission member in a direction opposite to that in which the belt element tends to move over the table top, and to shift the table top to the limit of its travel in that direction.

2. A manipulable feed table comprising a frame, a structural top slidably mounted thereon, said top being supported to reciprocate easily along a fixed path between two termini, journaled rollers at the ends of said structural top, a plurality of endless belt elements encircling said rollers and frictionally engaging the latter, said belt elements overlying and bearing upon said top intermediate said rollers and defining, with said top, a work supporting surface, a rotary operating element secured to one of said journaled rollers, a motor-driven operating element secured to said frame, and an endless flexible transmission member engaging said operating elements, the operating drag of said belt elements being substantially greater than the frictional drag of said top upon said frame, said transmission element being operatively arranged to shift the top in one direction and to drive the belt in the opposite direction, whereby when power is applied, said rotary operating element tends to travel along the endless flexible transmission member in a direction opposite to that in which the belt elements tend to move over the table top, and to shift the table top to the limit of its travel in that direction.

3. A manipulable feed table comprising a frame, a structural top slidably mounted thereon, said top being supported to reciprocate easily along a fixed path between two termini, journaled rollers at the ends of said structural top,

and an endless belt element encircling said rollers and frictionally engaging the latter, said belt element overlying and bearing upon said top intermediate said rollers and defining, with said top, a work supporting surface, a rotary operating element secured to one of said journaled rollers, a motor-driven operating element secured to said frame, an endless flexible transmission member engaging said operating elements, and a series of guides on said frame and upon said top, respectively, defining a course having one elongated span extending longitudinally of the path of said slidable top, said guides holding said flexible transmission member in engagement with the rotary operating element independent of the position of the top with respect to said table or the movement of said top traversing said reciprocal path, the operating drag of said belt element being substantially greater than the frictional drag of said top upon said frame, said transmission element being operatively arranged to shift the top in one direction and to drive the belt in the opposite direction, whereby when power is applied, said rotary operating element tends to travel along the endless flexible transmission member in a direction opposite to that in which the belt element tends to move over the table top, and to shift the table top to the limit of its travel in that direction.

4. A manipulable feed table comprising a frame, a structural top slidably mounted thereon, said top being supported to reciprocate easily along a fixed path between two termini, journaled rollers at the ends of said structural top, an endless belt element encircling said rollers and frictionally engaging the latter, said belt element overlying and bearing upon said top intermediate said rollers and defining, with said top, a work supporting surface, a motor carried by said frame, a rotary operating member driven by said motor, a rotary operating element secured to one of said journaled rollers, and an endless flexible transmission member engaging said operating elements, the operating drag of said belt element being substantially greater than the frictional drag of said top upon said frame, said transmission element being operatively arranged to shift the top in one direction and to drive the belt in the opposite direction, whereby when power is applied, said rotary operating element tends to travel along the endless flexible transmission member in a direction opposite to that in which the belt element tends to move over the table top, and to shift the table top to the limit of its travel in that direction.
